UNITED STATES PATENT OFFICE.

JOHN McILVENNY, OF NORWICH, CONNECTICUT.

GARMENT-SUPPORTING CLASP.

1,212,529.

Specification of Letters Patent. Patented Jan. 16, 1917.

Application filed November 17, 1915. Serial No. 62,012.

To all whom it may concern:

Be it known that I, JOHN McILVENNY, a citizen of the United States, residing at Norwich, in the county of New London and 5 State of Connecticut, have invented certain new and useful Improvements in Garment-Supporting Clasps, of which the following is a full, clear, and exact specification.

10 This invention relates to clasps, and has for its object to provide a clasp especially adapted for supporting garments, such as trousers and skirts, in clothes closets, and to this end is provided with means for securing the same to the wall of the closet or to a shelf therein.

Another object is to facilitate the release or opening of the clasp when the same is attached to the wall or shelf of a closet.

20 A further object is to simplify the construction of the clasp so that it may be economically manufactured.

Other objects will appear as the description proceeds.

25 The invention will be described first in connection with the accompanying drawings, which constitute a part of this specification, and then more specifically defined in the claims at the end of the description.

30 In the accompanying drawings, wherein similar reference characters are used to designate corresponding parts throughout the several views: Figure 1 is a perspective view of a clasp constructed substantially in accordance with the present invention, the supporting hook being shown in full lines in the position it occupies when screwed into the bottom of the shelf, and in dotted lines in the position it assumes when screwed into 35 the wall of a closet, and the open position of the clasp being illustrated in dotted lines. Fig. 2 is a sectional view taken in the line II-II of Fig. 3. Fig. 3 is a transverse section through the clasp, and Fig. 4 is a broken 40 view illustrating how a pair of the clasps may be fastened to a shelf and used for supporting a pair of trousers.

In the drawings, 1 designates a supporting hook having its end pointed and screw-threaded, as at 2, for fastening to a fixture, such as a wall or shelf, see Fig. 4. The head of the hook has a straight portion 3 which extends through the body of the clasp and

also serves as the pivotal axle for the swinging jaw member of the clasp. 55

The body of the clasp is preferably made in a single piece consisting of a relatively long rear arm 4, depending from a central portion 5, and a relatively short front arm 6, the latter having its lower end turned inward, as at 7, to form the fixed jaw of the clasp. The central portion 5 at the crotch between the arms 4 and 6 has lateral depending flanges 8 which are perforated at 9 for the passage of the straight portion 65 3 of the supporting hook 1. The arms 4 and 6 preferably diverge slightly from the central portion 5, and are provided with longitudinal inwardly turned flanges 11 and 12, respectively, which serve to stiffen these 70 parts and permit them to be made of comparatively thin metal.

The straight portion 3 of the hook is also passed through ears 14 on the upper end of the movable or swinging jaw member 13, 75 thus forming the pivotal axle for said movable jaw between the arms 4 and 6 of the rigid body or frame of the clasp. Said movable jaw member 13 has an outward offset 15 opposite the fixed jaw at the lower 80 end of the arm 6, and this offset constitutes the movable jaw proper. The swinging member extends downwardly beyond the offset 15 to form a finger piece 16 arranged opposite the lower end of the arm 4. The 85 swinging member is normally pressed outward away from the arm 4 and toward the arm 6 by a spring 10 coiled about the straight portion 3 of the hook and having one of its ends bearing against the arm 4 90 and its other end pressing against the movable jaw member 13. The flange 11 at one edge of the arm 4 retains the end of the spring which bears against said arm in proper position, while a similar inwardly 95 turned flange 17 on the swinging member 13 holds the other end of the spring in place against that part. It will be noted that the flanges 8 at the sides of the top portion 5 of the rigid frame or body of the 100 clasp serve to house the spring 10 and retain the movable member in operative position.

As illustrated in Fig. 4, the hook 1 may have its screw-threaded end 2 screwed into 105 the bottom of a shelf 18 for supporting the

clasp in a convenient position. If desired, however, the hook 1 may be turned down to a horizontal position, as suggested in dotted lines in Fig. 1, and screwed into 5 a vertical surface or wall. In fact, the hook may be turned with its screw-threaded shank 2 at any desired angle with respect to the frame of the clasp, thus adapting said clasp to be fastened up and supported from 10 fixtures in various positions as may be best suited for holding different garments. As shown in Fig. 4 a pair of the clasps are arranged in proper position for supporting a pair of trousers 19, the bottoms of which 15 are gripped between the fixed jaws 7 and movable jaws 15 of the clasps. To release the garment and open the clasps, the finger piece 16 of the movable member, and the lower end portion of the arm 4 of the rigid 20 frame are grasped between the forefinger and thumb, and the movable member 13 pressed or swung inward toward the arm 4, consequently, away from the arm 6 and fixed jaw 7. 25 The construction of the clasp with the finger piece 16 at the end of the movable jaw facilitates the insertion of the article to be supported between the jaws of the clasp. By grasping either the waistbands 30 or bottom of the garment between the thumbs and forefingers of the hands and pressing the garment thus held against the finger piece 16 the latter may be swung inward sufficiently to open the clasp wide 35 enough to admit the edge of the garment which may be easily inserted between the jaws while said finger piece is thus held. As soon as pressure is removed from the finger piece, the movable jaw will be closed 40 by the spring, thus clamping and securely holding the garment to be suspended.

Copies of this patent may be obtained for five cents each, by addressing the "Commissioner of Patents, Washington, D. C."

Having thus described my invention, what I claim as new and desire to secure by Letters Patent of the United States is:

1. A clasp comprising a rigid frame having spaced arms, one of which has its extremity turned inward toward the other arm to form a fixed jaw, a movable jaw member pivoted at one end between the arms of the frame and having an outwardly offset portion intermediate of its ends and opposite the fixed jaw, said offset portion constituting a movable jaw, said pivoted member also having a finger piece extending beyond the offset, and resilient means for 55 pressing the movable jaw against the fixed jaw.

2. A clasp comprising a rigid frame having spaced arms, one of which constitutes a fixed jaw, a pivotal axle carried by the 60 frame and arranged between the arms, a movable jaw member pivoted on said axle, and a spring coiled about the axle and having its ends bearing against the movable jaw member and one arm of the frame for 65 pressing said movable jaw member against the other arm of the frame.

3. A clasp comprising a rigid frame having spaced arms, one of which constitutes a fixed jaw, and lateral flanges in the crotch 70 at the junction of said arms, a pivotal axle passed through said flanges, a movable jaw member pivoted on said axle between said flanges, and a spring coiled about the axle and having its ends bearing against the 75 movable jaw member and one arm of the frame for pressing said movable jaw member against the other arm of the frame.

In testimony whereof I have signed my name to this specification.

JOHN McILVENNY.
